COMBINED STORAGE AND DISPLAY STAND FOR IRONING TABLES OR THE LIKE

Robert J. Wagner, Feasterville, Pa., assignor to The Proctor-Silex Corporation, Philadelphia, Pa., a corporation of Connecticut

Filed Aug. 31, 1962, Ser. No. 71,517

Term of patent 14 years

(Cl. D80—11)

FIG. 4.

FIG. 6.

FIG. 5.

FIG. 1 is a front perspective view taken from one side of a combined storage and display stand for ironing tables or the like showing my new design; the door being in an open position;

FIG. 2 is a front elevational view thereof;

FIG. 3 is a top plan view thereof;

FIG. 4 is a rear elevational view thereof;

FIG. 5 is a bottom plan view thereof;

FIG. 6 is an elevational view taken from the side opposite that shown in FIG. 1; and

FIG. 7 is an enlarged cross-sectional view thereof taken on line 7-7 of FIG. 2.

I claim:

The ornamental design for a combined storage and display stand for ironing tables or the like, as shown.
